HOLDER FOR CASSETTES OR THE LIKE

Hormoz Rafaat, 709 Narcissus, Corona
Del Mar, Calif. 92625

Filed Jan. 2, 1975, Ser. No. 537,956

Term of patent 7 years

Int. Cl. D6—04

U.S. Cl. D6—189

FIG. 1.

FIG. 2.

FIG. 3.

FIG. 4.

FIG. 5.

FIG. 6.

FIG. 1 is an isometric view of a holder for cassettes or the like embodying my new design:

FIG. 2 is a front elevational view of the holder for cassettes or the like;

FIG. 3 is a side elevational view of the holder for cassettes or the like illustrating the side of the holder which is hidden from view in FIG. 1;

FIG. 4 is a rear elevational view of the holder for cassettes or the like;

FIG. 5 is a top plan view of the holder for cassettes or the like; and

FIG. 6 is a bottom plan view of the holder for cassettes or the like.

I claim:

The ornamental design for a holder for cassettes or the like, substantially as shown.
